US00D941163S

(12) **United States Design Patent** (10) Patent No.: **US D941,163 S**
Cooper et al. (45) Date of Patent: ** Jan. 18, 2022

(54) **STENCIL OF A MEDIA METERING DEVICE**

(71) Applicant: **The Nielsen Company (US), LLC**,
New York, NY (US)

(72) Inventors: **Timothy Scott Cooper**, Oldsmar, FL
(US); **Saso Vranek**, Ilirska Bistrica
(SI); **Michael Alan Hicks**, Clearwater,
FL (US); **James Joseph Vitt**, Palm
Harbor, FL (US)

(73) Assignee: **The Nielsen Company (US), LLC**,
New York, NY (US)

(**) Term: **15 Years**

(21) Appl. No.: **29/631,566**

(22) Filed: **Dec. 29, 2017**

Related U.S. Application Data

(62) Division of application No. 29/569,285, filed on Jun.
24, 2016, now Pat. No. Des. 809,941.

(57) **CLAIM**

The ornamental design for a "stencil of a media metering device," as shown and described.

DESCRIPTION

FIG. 1 is a front right perspective view of a stencil of a media metering device.

FIG. 2 is a front view of the stencil of FIG. 1.

FIG. 3 is a rear inverted view of the stencil of FIG. 1.

FIG. 4 is a right side view of the stencil of FIG. 1.

FIG. 5 is a left side view of the stencil of FIG. 1.

FIG. 6 is a top view of the stencil of FIG. 1; and,

FIG. 7 is a bottom view of the stencil of FIG. 1.

The features shown in broken lines form no part of the claimed design. The dot-dashed lines define boundaries and form no part of the claimed design. The front surface surrounded by the solid line forms no part of the claimed design.

1 Claim, 1 Drawing Sheet
